A. H. WATSON

AWNING FOR MOTOR VEHICLES

Filed Nov. 12, 1925

Patented July 5, 1927.

1,634,860

UNITED STATES PATENT OFFICE.

ARTHUR H. WATSON, OF CHICAGO, ILLINOIS, ASSIGNOR, BY DIRECT AND MESNE ASSIGNMENTS, TO RICHARD C. POTTER, OF RIVERSIDE, ILLINOIS.

AWNING FOR MOTOR VEHICLES.

Application filed November 12, 1925. Serial No. 68,526.

My invention relates to improvements in awnings for motor vehicles and it consists in the combinations, constructions, and arrangements herein described and claimed.

5 An object of my invention is to provide an awning of the character described in which particularly novel means is employed for detachably securing the awning in place upon the window sash structure of a motor vehicle, so that the awning will project outwardly therefrom to protect the occupants of the vehicle from the glare of the sun's rays, and yet which does not obscure vision.

A further object of my invention is to provide an awning of the character described which when detached from the window or door window sash occupies a space sufficiently small to permit the awnings to be placed within the usual door pockets provided in the doors of motor vehicles.

25 A further object of my invention is to provide an awning of the character described which is so constructed as to permit of the permanent adjustment of the length of the awning so as to fit the sash of a particular vehicle at the precise time of installation. This precludes the necessity of a dealer carrying a large stock of awning of various predetermined sizes.

30 A further object of my invention is to provide an awning of the character described which can be manufactured at an exceedingly low cost, which is durable in structure and which is thoroughly practical for the purposes intended.

Other objects and advantages will appear in the following specification and the novel features of the invention will be particularly set forth in the appended claim.

40 My invention is illustrated in the accompanying drawings forming a part of the specification in which

Figure 1 is a plan view of an embodiment of my invention in place upon a motor vehicle window sash,

45 Figure 2 is a sectional view along the line 2-2 of Figure 1, slightly enlarged,

Figure 3 is an enlarged fragmentary view of a part of the device illustrated in Figure 50 1, in the process of installation, and

Figure 4 is a sectional view along the line 4-4 of Figure 3.

In carrying out my invention I make use of the ordinary type of motor vehicle door window sash 1. It should be well to note

at this time that my awning is intended for use upon the sash of the windows in the door as well as in the body portion or tonneau proper of the vehicle. The sash 1 is provided with a glass pane 2 which is adapted for movement vertically of the sash in felt slideways 3.

Prior to the installation of my improved awning I place a plurality of snap fasteners 4 at predetermined distances from one another along the upper horizontal portions of the sash 1. These fasteners are similar in construction to the well known type of snap glove fastener employed on wearing apparel.

The fasteners 4 are secured to the sash 1 by the provision of shanks 5 having wood screw threads formed thereon, which are turned into the wooden structure of the sash. If the sash is of steel structure I then employ a shank having machine screw threads thereon, and employ a drill and tap in preparing the sash for the fasteners.

A pair of spaced apart mushroom-head buttons is fastened to each of the vertical sections of the sash adjacent to the horizontal portion referred to. These buttons are secured to the sash by integral shanks similar to those employed for securing the snap fasteners 4 in place.

My improved awning consists principally of three parts, an awning strip 7, having a fringe 8 at the lower edge thereof, and a pair of fastening plates 9 which perform the two fold function of supporting the ends 90 of the awning and which provide closures at the end portions of the awning.

The awning strip 7 has its upper edge folded horizontally as shown at 10 so as to obscure the cut edge thereof, and so as to reinforce the edge, and has a plurality of complementary snap fasteners 11 projected therethrough which are adapted to register and engage with the snap fasteners heretofore described. Thus the upper edge of the awning strip may be securely fixed against unintentional movement with respect to the horizontal upper portion of the sash 1. The inherent properties of the fasteners readily permits the awning to be attached and detached to and from the sash 1 at this edge.

The end plates 9 are of substantially rigid sheet metal which are enamelled in colors to harmonize with the coloring of the awning 110

strips 7, or with the color of the finish on the tonneau of the vehicle. The awning strips 7 are preferably constructed of canvas awning stock, but may be made of leatherette or other similar material if desired.

The end plates 9 are each substantially triangular in contour as shown in Figure 2, and each is provided with portions 12 perpendicular to the major portion thereof which portions are arranged to lie in close engagement with the inner faces of the upper portions of the side members of the sash 1, adjacent to the pairs of buttons 6. The portions 12 are further provided with openings therethrough having connected enlarged and constricted portions 13 and 14 respectively. The buttons 6 are permitted to pass through the portions 13 of the openings when the plates are moved against the adjacent faces of the sash portions as described. Upon the upward vertical movement of the plates the shanks of the buttons 6 occupy the constricted portion 14 of the openings thereby securely locking the plates against the lateral movement thereof.

The ends of the awning strip 7 are engaged with laterally extended convoluted portions 15 of the plates 9, see Figure 4, which entirely encompass the frayed ends 30 of the awning strip, and which serve to securely grip the ends of the awning strip. The strip 7 is cut to the length desired subsequent to the installation of the plates 9 upon the sash, and are then secured to the convoluted portions 15 of the plates, by any well known means. In the present embodiment of the invention I have embossed the convoluted portions 15 longitudinally as shown at 16 to secure the ends of the strip 40 7 to the plate, though rivets or the like may be employed equally as well.

From the foregoing description of the various parts of my invention the operation may be readily understood. During the 45 time when my improved awning is not in actual use the awning strip 7 may be folded compactly between the opposed end plates 9

and thus may occupy so small a space as to permit the awning to be placed entirely within the pockets usually provided in the door of the vehicle. This feature is made possible by the novel structure of the awning which precludes the necessity for employing rigid rods or the like which extends longitudinally of the awning.

When it is desired to place the awning in its operative position upon the sash of the door window or window of the tonneau I first engage the plates 9 with the mushroom button 6 by projecting the buttons through the 55 openings in the portions 9. I next draw the awning strip 7 upwardly which movement also elevates the plates 9 and secures the fasteners 11 in place upon and in engagement with the fasteners 4. This maintains the 60 plates 9 in an elevated position so that the mushroom heads of the buttons 6 overlie those portions of the plate 9 surrounding the constricted part 14 of the plate openings.

In this manner a complete awning is provided, the plates 9 forming end closures for the awning strip as well as a means of support for maintaining the awning strip taut. The awnings do not project outwardly any 75 farther than the running board or the fenders of the motor vehicle, yet effectually shade the interior of the tonneau so that persons sitting therein may not be in direct sunlight, as must necessarily be the case where my improved awnings are not employed.

I claim:

The combination with a vehicle having window sashes, of fastener members secured to the sashes, an awning strip, end plates 85 fixed to the outer ends of the strip forming end closures for the awnings, plate engaging members carried by the sashes for securing the plates to opposite side portions of the sash, and complementary fastener members carried by the awning strip for engaging with the first named fastener members.

ARTHUR H. WATSON.
